(57) **CLAIM**

The ornamental design for a cooking apparatus, as shown and described.

DESCRIPTION

FIG. 1 is a top perspective view of a first embodiment of a cooking apparatus in accordance with the subject disclosure. FIG. 2 is a left side view of the cooking apparatus of FIG. 1.

FIG. 3 is a right side view of the cooking apparatus of FIG. 1.

FIG. 4 is a front view of the cooking apparatus of FIG. 1.

FIG. 5 is a rear view of the cooking apparatus of FIG. 1.

FIG. 6 is a top view of the cooking apparatus of FIG. 1.

FIG. 7 is a bottom view of the cooking apparatus of FIG. 1.

FIG. 8 is another top perspective view of the cooking apparatus of FIG. 1.

FIG. 9 is a bottom perspective view of the cooking apparatus of FIG. 1; and,

FIG. 10 is a top perspective view of a second embodiment of the cooking apparatus of FIG. 1 indicating surface shading for metal.

In alternative embodiments, the cooking apparatus may have different numbers or sizes of perforations, or no perforations at all. Further, the cooking apparatus may have different shaped handles, upper edges, or lower edges. In various embodiments, the legs supporting the cooking apparatus may be of a different number or shape, or the legs may be spaced differently.

The broken line showings are included for the purpose of illustrating portions of the invention and form no part of the claimed design.
